OCCLUDER FOR VISION TESTING

Henry F. Allen, Boston, Mass.

Application August 15, 1956, Serial No. 42,616

Term of patent 7 years

(Cl. D57—1)

The single figure of the drawing is a perspective view of an occluder for vision testing, showing my new design.

The rear of the design, not shown, is the same as the side shown.

I claim:

The ornamental design for an occluder for vision testing, as shown and described.
